United States Patent Office

Des. 193,485
Patented Aug. 28, 1962

193,485

FLOWER POT

William John White, 991 S. State Road 7,
Fort Lauderdale, Fla.

Filed Feb. 28, 1962, Ser. No. 69,019

Term of patent 14 years

(Cl. D35—3)

Fig. 2.

Fig. 4.

Fig. 1.

Fig. 5.

Fig. 3.

I claim:

The ornamental design for a flower pot, as shown.
